UNITED STATES PATENT OFFICE.

JAMES F. THORNTON, OF NICHOLAS COURT-HOUSE, WEST VIRGINIA.

CAR-COUPING.

SPECIFICATION forming part of Letters Patent No. 378,409, dated February 21, 1883.

Application filed November 19, 1887. Serial No. 255,644. (No model.)

To all whom it may concern:

Be it known that I, JAMES F. THORNTON, of Nicholas Court-House, in the county of Nicholas and State of West Virginia, have invented a new and useful Improvement in Car-Couplings, of which the following is a specification.

This invention is an improved car-coupling seeking to provide simple and convenient means whereby the cars may be coupled or uncoupled without necessitating the operator going between the cars.

The invention consists in certain features of construction and novel combinations of parts, as will be hereinafter described and claimed.

In the drawings, Figure 1 is a side elevation of two cars provided with the improvements. Fig. 2 is a perspective view of the improvements in place on a car, dotted lines being employed to indicate different positions of some of the parts. Fig. 3 is a detail view of the cross-head; Fig. 4, a detail view of one of the grapple-bars; Fig. 5, a horizontal longitudinal section of the draw-head. Fig. 6 is a detail view of the pin-bar, and Fig. 7 a detail view of the coupling-link.

To the car is connected a draw-head, A, which forms a support for the grapple-arms B, and which has a link-mortise, a, and a suitable pin-opening. Within this link-mortise a, I arrange springs C, secured at their forward ends and converging toward their rear or free ends, as shown in Fig. 5. These springs serve to prevent any rattling movement of the link D when in the draw-head, ease the entrance of said link, and at the same time permit the lateral play of such link desirable in the passage of trains around curves and bends.

The grapple arms or bars B are pivoted at their rear ends to the draw-head or other suitable support, and are provided at their forward ends with the grapples or hooks b. These arms, by reason of their pivot, as described, may be adjusted to the position shown in full lines, Fig. 2, over the draw-head, or to the dotted position, same figure, where they rest at right angles to the direction of length of the draw-head. I provide latches E, by which the bars B may be secured in either one of such positions, such latches by preference being spring-plates secured at one end to the arms, and having pins e at their opposite

ends, which project through the arms and enter sockets in the draw-head or in short bars or projections F, extended from the end of the car, as the case may be. When in position over the draw-head, the grapples or hooks of the arms B project beyond the end of the draw-head, as will be seen in Fig. 1.

The coupling-pin g is formed or secured on the lower end of the vertical bar G, which extends upward through a guide, G', to or nearly to the top of the car, and is preferably actuated by a spring or springs, H, which give the bar a downward tension. This bar, it will be seen, may be reached and operated by a person on top of the car, and to facilitate its operation from the side of the car I provide a lever, I, pivoted between its ends, connected at one end with the vertical bar and having its other end extended to the side of the car.

On the vertical slide-bar I pivotally support what may be termed the "cross-head" J, which has a stem, j, extended at right angles from its rear end, and the pivot of the cross-head is preferably arranged near the extremity of such stem. When in operative position, the cross-head rests near to the top of the draw-head, and is held in such position by a latch or slide bolt, K, on the under side of the cross-head entering a socket, k, in the slide-bar G. To adjust the cross-head out of operative position the latch K should be released, the cross head turned on its pivotal connection with the slide-bar, and the bolt K be adjusted into the upper socket, k', in the slide-bar.

It will be seen that one of my improved couplings can be conveniently coupled with an ordinary coupling by the common link; but it is preferred to use two of my couplings in conjunction.

In operation the coupling devices on one car are adjusted as follows: The grapple-arms are extended over the draw-head and secured with the grapples or hooks projected beyond the end of the draw-head, and the cross-head of such car is preferably adjusted up out of operative position, and the link is secured in the draw-head. On the other car the grapple-arms are turned outward against the ends of the car, and the cross-head is lowered into operative position. If these two

cars be now brought together, the cross-head of the latter one will engage the grapples or hooks of the arms B, and be raised thereby to pass over and engage the shoulders of the 5 grapples. This elevation of the cross-head effects the elevation of the slide-bar and pin, so that the link held by the opposite draw-head will pass under the pin when elevated by the inclines of the grapples, which pin will 10 lower into and secure the link when the cross-head moves into proper engagement with the grapples. Thus the adjustment of one set of devices to coupled position operates to adjust another set of devices to coupled position, a 15 double coupling being thus effected.

As the said devices operate together and coact as described, it is preferred to use them together, as shown; but it is manifest they may 20 be used alone without departing from some of the broad features of my invention.

The construction, it will be seen, is simple, and can be readily applied or added to the ordinary draw-head without requiring any considerable change or alteration in said draw-head.

25 Having thus described my invention, what I claim as new is—

1. In a car-coupling, the combination of the draw-head, the slide-bar extended to or nearly to the top of the car and having the coupling-pin at its lower end, and a spring or springs 30 for depressing said slide-bar, substantially as set forth.

2. In a car-coupling, the combination of the draw-head and the grapples or hooks extended 35 thereover and separated, forming a way between them for a part on a meeting draw-head, substantially as set forth.

3. In a car-coupling, the combination, with a draw-head or support, of grapple-arms pivoted at their rear ends and movable laterally 40 in opposite directions onto and off the draw-head or support, substantially as set forth.

4. In a car-coupling, a draw-head or support and grapple arms or bars pivoted at their 45 rear ends, whereby they may be adjusted or swung laterally, as described, in combination with latches or detents for securing said arms in their different adjustments, substantially as set forth.

5. The combination, with the draw-head or 50 support, the projections F on opposite sides thereof, and the grapple-arms pivoted at their rear ends, whereby they may be turned laterally inward over the support or outward over projections F, of the latches consisting of 55 spring-plates secured at one end to the arms and provided at their free ends with pins to enter sockets in the draw-head or support, and the projections F in the different adjustments of the grapple-arms, substantially as set forth. 60

6. In a car-coupling, the combination, with the draw-head and suitable guides, of the slide-bar movable vertically in said guides and extended approximately to the top of the car, and the coupling-pin rigidly connected with 65 the lower end of the slide-rod, substantially as set forth.

7. In a car-coupling, a vertically-movable slide-bar provided with a cross-head arranged to be engaged by grapples or hooks of a meeting coupling, substantially as set forth. 70

8. In a car-coupling, the combination of the draw-head having a link-mortise and the vertical slide-bar provided with a cross-head and with the coupling-pin, whereby the pin 75 may be elevated for the insertion of the link by the contact of the cross-head with the grapple hooks or bars, substantially as set forth.

9. The vertical slide-bar, combined with the cross-head, pivotally connected therewith, 80 whereby it may be elevated out of operative position, and a latch for securing the cross-head in its different adjustments, substantially as set forth.

10. The combination of the draw-head, the 85 grapple-bars, and the vertical slide-bar provided with the coupling-pin and with the cross-head, substantially as and for the purposes specified.

11. The combination of the draw-head, the 90 grapple-bars pivoted at their rear ends and adjustable over said draw-head, the vertical slide-bar, and the cross-head supported thereby, substantially as set forth.

JAMES F. THORNTON.
